UNITED STATES PATENT OFFICE.

CHARLES E. WARD, OF CHARLESTON, WEST VIRGINIA.

RUDDER CONTROL FOR TOWBOATS.

Application filed September 14, 1927. Serial No. 219,515.

This invention relates to rudder constructions for tow boats and the like and has for its object to provide a construction more efficient in use than those heretofore proposed.

- 5 With these and other objects in view, the invention consists in the novel details of construction and combinations of parts more fully hereinafter disclosed and particularly pointed out in the claims.
- 10 Referring to the accompanying drawings forming a part of this specification in which like numerals designate like parts in all the views:

Fig. 1 is a diagrammatic top plan view of 15 the stern of a boat made in accordance with this invention;

Fig. 2 is a view somewhat similar to Fig. 1 but directed to illustrating the rudders in a different position, and the screws rotating 20 in opposite directions;

Fig. 3 is a view similar to Fig. 2 with the screws rotating in the same direction and the rudders in still further different position;

Fig. 4 is a view similar to Fig. 1, but illustrating a different system of control for the 25 rudders;

Fig. 5 is a view similar to Fig. 4 illustrating the flow of wheel water against the rudders;

Fig. 6 is a longitudinal sectional view taken 30 as on the line 6—6 of Fig. 1 and looking in the direction of the arrow;

Fig. 7 is a view similar to Fig. 4 but illustrating still another control for the rudders;

Fig. 8 is a longitudinal sectional view taken 35 through a propeller but illustrating the invention as applied to a shallow draft tunnelless boat;

Fig. 9 is a transverse sectional view taken 40 as on the line 9—9 of Fig. 6 and looking in the direction of the arrow; and

Fig. 10 is a transverse sectional view taken 45 as on the line 10—10 of Fig. 8 and looking in the direction of the arrow.

A tow boat is generally indicated at 1 and 50 comprises the main bottom 2, the sides 3, and the stern 4. The main bottom 2 is substantially parallel with the gunwales 5 and the water line indicated by the line 6, see Fig. 6.

Near the stern, the bottom 2 is inclined upwardly as indicated at 10 and is provided 55 with a plurality of tunnels or chambers 11, as well understood in ships of this character and as clearly shown in the drawings. The bottom 10 in forming these tunnels 11 also

forms a secondary bottom 12 as clearly shown in Fig. 6, which is disposed below, and inclined at a slight angle to, the water line 6, extending upwardly toward the stern.

The cross section of the tunnels 11 at the deepest portions thereof is substantially circular and within this circular formation are located the screw propellers 15 mounted on the shafts 16 and journalled as diagrammatically illustrated at 17 in the drawings. The 60 propellers and their shafts together with the tunnels 11 associated therewith, are all so disposed relative to each other that each propeller 15 will be located in a tunnel 11, and above the main bottom 2 of the boat, see Fig. 6. Further, the propellers 15 are disposed in a common transverse plane as represented by the line 20 in Fig. 2.

With special reference to Fig. 2, it will be observed that there is provided a plurality 75 of aft rudders 21 whose stems or axes 22 are located in the same transverse plane indicated by the line 23 which is substantially parallel with the plane 20 passing through the propellers 15 and with reference to Fig. 6 it will be 80 observed that the top surfaces of the rudders 21 do not extend above the secondary bottom 12, so that said rudders may be freely turned beyond the extremities of the tunnels of the boat. Each rudder 21 is further disposed adjacent a propeller 15 so that the stem of said rudder is in the same longitudinal plane of the vessel with the shaft of the propeller, and spaced aft of said propeller so 85 that the rudder may freely swing without interfering therewith.

Also referring to Fig. 2 it will be seen that there is provided another plurality of rudders 25 the stems 26 of which are disposed in a transverse plane indicated by the line 27 95 which is substantially parallel with the plane 20 of the propellers 15 and spaced forward thereof a sufficient distance to freely permit the swing of each rudder 25 without interfering with a propeller. Also it is to be observed that each rudder 25 is mounted along the lateral extremity of a tunnel 11; or stated in other words, on either side of each tunnel 11 there is disposed a forward rudder 25, and with reference to Fig. 6 it will be seen 100 that the top surface of each forward rudder is disposed substantially flush with the secondary bottom 12 of the boat.

Referring now to Fig. 1 it will be seen that 105 all of the forward rudders 25 have their 110

stems interconnected as by the link bar 30 so that all of said rudders are moved in unison by any suitable means such as the operating rod 31 pivoted as at 32 to one end 5 of a crank 33 the other end of which is rigidly secured to a stem of one of the rudders 25. It will also be seen that all of the aft rudders 21 have their stems interconnected as by the bar 35 so that said rudders are 10 moved in unison upon operating the rod 36 pivoted as at 37 to one end of a crank 38 the other end of which is rigidly secured to a stem of one of the rudders 21. The interconnections between the forward rudders as well as 15 the interconnections between the aft rudders are such that each set of rudders will not only move in unison but will at all times be parallel. In other words, in Fig. 1 is disclosed a means of operating a plurality of 20 forward rudders in parallel unison, and a separate or independent means of moving the aft rudders in parallel unison. The result of this rudder control is that when the vessel is moving ahead as indicated by the arrow 25 in said figure, the aft rudders may be set and held on the center line so as to offer the least possible resistance to the vessel through the water and the water flowing to the propellers which are going astern and thus forcing water against the forward rudders which 30 may be set for the desired movement of the stern of the vessel. If the vessel is desired to be moved astern in a straight line, the forward rudders will be operated to place the same on the center line, but should the stern of the vessel be desired moved in the direction 35 of the arrow in said Fig. 1 while the propellers are backing, the forward rudders will be moved obliquely to such a position as indicated in said figure and the propellers 40 rotated to force the water in the direction of the arrows, whereupon the water will freely pass the aft rudder but will be forced by said propellers against an oblique surface 45 of each of the forward rudders and diverted therefrom with resultant movement of the stern of the vessel to starboard. In the conditions 50 illustrated in Fig. 1 namely, moving the stern of the vessel to starboard while backing, the propellers which are rights and lefts are rotated in opposite directions as indicated to produce the movement or flow of water to the forward rudders. The natural movement of the vessel ahead will of course 55 be diminished by the reversal of rotation of the propellers and resistance offered by the forward rudders which are moved hard over.

Referring now to Fig. 2 it will be seen that the right and left propellers are likewise rotated in opposite directions, but in such a direction as to force the water therefrom astern 60 for movement of the vessel in the forward direction as indicated by the arrows. In the particular arrangement of rudders shown in 65 this figure, the forward rudders offer little

or no resistance to the water flowing to the propellers but the aft rudders are set hard over so that said water will be forced by the propellers against an oblique side of the aft rudders and be deflected therefrom to 70 produce movement of the stern of the vessel to starboard.

From Figs. 1 and 2 it will therefore be readily seen that there is provided positive means for permitting the flow of water to 75 the propellers which is forced thereby against the other set of rudders for producing directional movement of the stern of the vessel as desired, and in accordance with the longitudinal directional travel of the boat. 80

In Fig. 3 is disclosed a different condition and from which it will be observed that the aft interconnected rudders 21 and the forward interconnected rudders 25 are each, as a group, set hard over to produce a different 85 movement of the vessel. That is to say, the forward rudders are set and held hard over in one direction whereas the aft rudders are set and held hard over in the opposite direction, and the right and left propellers 15 90 rotated in the same direction. With this arrangement of control, the vessel will be given no longitudinal movement but the stern of the vessel will be moved to starboard as shown by the arrows. The reason for this 95 will be obvious from the said Fig. 3, but may be stated as being the result of the port propeller forcing the water ahead while the starboard propeller is forcing the water astern, each propeller thus counteracting the work 100 performed by the other. The water forced by the port propeller strikes an oblique surface of the pair of forward rudders associated therewith, and is deflected therefrom in a direction to produce movement of the stern 105 of the vessel to starboard. Likewise the water moved by the starboard propeller is forced astern against the oblique face of the starboard aft rudder 21 and deflected therefrom in a direction to also produce a starboard swing of the stern of the vessel, thus 110 augmenting the action produced by the port propeller and its associated forward rudders. In this connection it is to be observed also that the water forced by the starboard propeller astern is directed into a natural channel created by the two parallelly disposed aft rudders. And further that the water forced by the port propeller in a forward direction 115 will pass through the natural channel provided therefor by the port pair of forward rudders thus minimizing a circular movement or whirl of water between the two propellers before accomplishing positive work in movement of the vessel through the medium of 120 the rudders.

With reference to Fig. 4 a slightly different rudder control is disclosed. In this arrangement the port forward rudders are connected for parallel movement in unison, and 130

this pair of rudders is linked to the starboard aft rudder so that all three rudders are simultaneously moved upon actuation of the rod 40. In other words, this rod is pivotally connected as at 41 to one end of a crank 42 the other end of which is rigidly secured to the stem of the outer port forward rudder 25, the stem of which is interconnected as by the link 43 to the stem of the next adjacent forward rudder 25, the stem of which is in turn connected as by the link 44 to the stem of the starboard aft rudder 21, the link 44 being so connected as to provide the same amount of circular movement of the aft starboard rudder as is given to the forward rudder to which it is connected, but this connection is not adapted to provide a parallel movement in unison between the aft rudder and the pair of forward rudders to which it is connected, as will be evident from said figure.

Likewise a rod 50 is pivoted as at 51 to one end of a crank 52 the other end of which is rigidly secured to the stem of the outer one of the pair of starboard rudders 25, and said rudder is connected as by the link 53 to the stem of the adjacent forward rudder of said pair, to insure parallel movement in unison of said pair of rudders. Also the stem of the inner of said pair of rudders is interconnected as by the link 54 to the stem of the port aft rudder 21 to produce simultaneous movement thereof with the forward starboard pair of rudders, but said connecting link 54 is not adapted to produce a movement of the port aft rudder at all times parallel with its associated pair of forward starboard rudders. However, as clearly indicated in Fig. 4, the aft rudder and its connected and associated pair of forward rudders will all be parallel when said rudders are held on the center line.

With such an arrangement of rudders as disclosed in Fig. 4, and with the right and left propellers 15 rotating in the same direction as indicated as by their arrows, and the rudders in the positions shown, there will be produced no longitudinal directional movement of the vessel but there will be produced a movement of the stern thereof to port as indicated by the arrow. The reason for this is that the oppositely formed propellers rotating in the same direction will negative each other as was the case as illustrated in Fig. 3. In other words, as clearly indicated in Fig. 5, the port propeller will force the water ahead against the oblique setting of the port forward rudders and this water coming from the rear must have no resistance offered thereto. Consequently it is necessary to have the port aft rudder on the center line. Also the starboard forward rudders must be on a center line to offer the least possible resistance to the starboard propeller which is forcing water astern against the hard over starboard aft rudder. This rudder effect is augmented by the side thrust of the propellers

rotating in a direction to produce a side thrust in the same direction as the rudders.

In Fig. 7 the forward rudders 25 are interconnected as by the rod 60 and the aft rudders 21 are likewise interconnected as by the rod 61, both of said rods being joined to a single operating rod 62 as through the respective pivoted cranks 63 and 64. Thus with the cranks of the same size, there will be an equal movement of the interconnecting rods 60 and 61. There will also be an equal rotation of the forward and aft rudders, if said rudders are of the same size, but if said rudders vary in size, or the points of connection between the rods 60 and 61 and the respective rudders are located at different distances from the stems of said rudders then there will be created an unequal turning movement of the forward rudders with respect to the turning movement of the aft rudders. Circumstances and requirements will determine the desirability of equal or unequal turning movements of the rudders and therefore changes will be made either in the pivotal distances of the rods with respect to the rudder stems, or in the dimensions of the arm of the cranks 63 and 64. With the rudder control illustrated in this figure and both propellers rotating in the directions indicated by the arrows, the wheel water will be forced in the direction indicated, and with the rudders all set on center line, a rearward movement of the vessel in the direction indicated by the arrow will result. Any turning of the rudders during said movement will give the usual port or starboard additional direction of travel of the vessel. It is to be noted that in this rudder control the forward rudders are still disposed at the lateral extremities of the tunnels 11, but the aft rudders are located in said tunnels in line with the longitudinal planes of the propeller shaft.

In Figure 8 is disclosed a vessel not provided with the tunnel construction but whose main bottom 2 is extended on an upward incline as indicated at 10 to a point just below the water line 6 to provide the secondary bottom 70. With this type of vessel the forward rudders are still located to either side of the propeller with which they are associated as clearly shown in Fig. 10 and the aft rudder, likewise in the longitudinal plane of the propeller shaft 16, is enlarged so as to extend substantially from the subsidiary bottom 70 to the main bottom 2, thus increasing the area of the aft rudder whereby the same is made more effective. The underlying principles of the invention are retained in both types of vessel, illustrated in Figures 6 and 8, namely, the provision of an aft rudder in longitudinal alignment with each propeller shaft, and a pair of forward rudders associated with each propeller and disposed in planes substantially tangent to the extremities of the propeller blades whereby at least one half of

the surface of each forward rudder receives the full effect of the water from each propeller, while said pair of forward rudders at all times creates a channel for the water, to or 5 from the associated propeller.

From all of the figures of the drawings it will thus be seen that this invention provides a control system for tow boats having a plurality of propelling screws therefor, a plurality of rudders associated with said screws 10 arranged in a plurality of transverse planes of the boat, and operating means controlling the rudders in said planes. Further, this particular arrangement of the rudders is such 15 that they are also arranged in a plurality of longitudinal planes one of which passes through the propeller shaft or sufficiently outside of said shaft to permit withdrawal of said shaft without removing a rudder, in 20 which case said rudder will be so constructed as to cover the same projected area of the propeller when said rudder is hard over. Still further all of the rudders are so disposed with 25 relation to the screws, that said screw is intermediate of the transverse and longitudinal planes passing through said rudders. This invention also contemplates the particular 30 control of the rudders whereby a pair of forward rudders is operated simultaneously and means provided for operating the aft rudder differently or unequally from the operation 35 of the forward pair of rudders. In the various connections between the rudders it is to be observed that such control covers the linking together of a pair of forward rudders and 40 that the control for this said pair of rudders not only produces simultaneous operation thereof, but keeps them in parallelism. Further the rudder connections are such that a 45 pair of rudders in one plane of the boat can be simultaneously operated differently and unequally from a rudder in another plane of the boat.

It is obvious that those skilled in the art 50 may vary the details of construction as well as the arrangements of parts without departing from the spirit of the invention, and therefore it is not desired to be limited to the foregoing disclosure except as may be required by the claims.

What is claimed is:—

1. In a control system for tow boats the 55 combination with a tow boat of a propelling screw therefor; a plurality of rudders one rudder located aft of said screw; and single means for simultaneously operating said rudders including means for differently operating the aft rudder.

2. In a control system for tow boats having 60 two laterally spaced screws the combination of a plurality of rudders one rudder located in line with but aft of one of said screws and a pair of rudders located forward of the other of said screws; and single means for operat-

ing said rudders in unity including means for 65 differently operating the aft rudder.

3. In a control system for tow boats the combination with a tow boat of a plurality of propelling screws therefor; a plurality of rudders for each screw one rudder located aft 70 of each screw and a pair of rudders located forward of each screw; and means for operating a forward pair of said rudders in unity with a diagonally opposite aft rudder.

4. In a control system for tow boats the 75 combination with a tow boat of a plurality of propelling screws therefor; a plurality of rudders for each screw, one rudder located aft of each screw and a pair of rudders located forward of each screw; and means for 80 operating a forward pair of rudders simultaneously; as well as for operating in unity therewith the diagonally opposite aft rudder differently from the operation of said forward pair of rudders.

5. In a control system for tow boats the combination with a tow boat of a plurality of propelling screws therefor; a plurality of rudders for each screw, one rudder located 90 aft of each screw and a pair of rudders located forward of each screw; and means for operating a forward pair of rudders simultaneously and similarly; as well as for operating in unity therewith the diagonally opposite aft rudder dissimilarly from the operation 95 of said forward pair of rudders.

6. In a control system for tow boats the combination with a tow boat of a plurality of propelling screws therefor; a plurality of rudders for each screw, one rudder located 100 aft of each screw and a pair of rudders located in a transverse plane of the boat said forward rudders being in planes substantially tangent to the extremities of the blades of the associated screw; means for operating 105 the rudders of each forward pair simultaneously in unison; as well as for operating differently in unity with each of said pairs the diagonally opposite aft rudder.

7. In a control system for tow boats the 110 combination with a tow boat of a plurality of rudders arranged in a plurality of transverse and longitudinal planes; a propelling screw intermediate said planes; and cross connections between said rudders whereby 115 a pair of rudders in one plane and a rudder in another plane can be simultaneously operated differently in unity.

8. In a control system for tow boats the combination with a tow boat of a propelling 120 screw therefor; a plurality of rudders one rudder located in substantial line with but aft of said screw and the other rudders located forward thereof; and single means for 125 differently operating in unity a forward and the aft rudder.

9. In a control system for tow boats having two laterally spaced screws the combina-

tion of a plurality of rudders one rudder located substantially in line with but aft of one of said screws and a pair of rudders located forward of the other of said screws; 5 and means for differently and simultaneously operating in unity a forward rudder and the aft rudder.

10. In a control system for tow boats the combination with a tow boat of a port side screw; a starboard screw; a plurality of rudders arranged fore and aft of each screw; and means for differently operating in unity the forward and aft rudders of opposite screws, said means including cross connections between the operated rudders.

11. A control system for tow boats comprising a starboard group of fore and aft

rudders with a propelling screw therebetween, a port group of fore and aft rudders with a propelling screw therebetween, and 20 cross connections between a forward rudder of one group and the aft rudder of the other group.

12. A control system for tow boats comprising a star board group of fore and aft 25 rudders with a propelling screw therebetween, a port group of fore and aft rudders with a propelling screw therebetween, a connection between a forward port and aft starboard rudder, and another connection between a forward starboard and aft port rudder.

In testimony whereof I affix my signature.

CHARLES E. WARD.
